UNITED STATES PATENT OFFICE.

JOHN WOLFE, OF PARIS, FRANCE.

CIGARETTE-PACKAGE HOLDER.

Application filed December 3, 1926, Serial No. 152,446, and in France July 31, 1926.

This invention relates to containers and has particular reference to a holder for cigarette packages.

The outstanding object of the present invention is to provide a cigarette package holder which serves as a means for preventing crushing of the package and its contents while permitting of the dispensing or withdrawal of the cigarettes.

10 The invention furthermore comprehends a holder for cigarette packages which includes a body preferably in the nature of a skeleton framework having a hingedly connected corner section capable of being swung 15 to an open position for exposing the torn-away corner of the package to allow for the removal of the cigarettes therefrom.

15 The invention aims as a further object to provide a cigarette package holder which is 20 comparatively simple in its construction, economical to manufacture, and which is highly efficient in its purpose.

With the above recited and other objects in view, reference is had to the following specification and accompanying drawings in which there is exhibited one example or embodiment of the invention which is in no way intended as a limitation upon the scope of the appended claim as it is to be clearly understood that variations and modifications which properly fall within the scope of said claims 30 may be resorted to when found expedient.

In the drawings—

Figure 1 is a perspective view of the holder or container with the package removed;

Fig. 2 is a similar view with the package in place;

Fig. 3 is a fragmentary sectional view through the corner equipped with the cover and illustrating the same in full and dotted lines in its closed and opened positions, respectively.

Referring to the drawings by characters of reference, the holder consists of a body preferably in the nature of a wire or open framework which includes a substantially rectangular rear frame 10 and a substantially rectangular front frame 11, the latter being of substantially lesser height than the former and connected thereto at the lower end by lower side rails 12. The upper end of the rear frame is connected by side rails 13 to a cross rail 14, which in turn is connected by

inclined rails 15 to the upper end of the front framework 11, thereby producing in effect 55 a framework having a cut-away corner at the upper forward end.

In order to retain the package P within the body, the rear frame 10 is provided with cross rails 16 and the front frame with a 60 cross rail 17. To prevent lateral displacement of the package, angularly disposed elements 18 extend from the frames 10 and 11, respectively, to the bottom and top side rails. This leaves the lower end of the body open 65 for the insertion and removal of the cigarette package P. A retaining element 19 in the nature of an arm is hinged at 20 to one of the lower side rails 12, the same being of a resilient material and formed at its free terminal with a catch 21 designed to engage over the opposite lower side rail 12 after the insertion of the cigarette package within the body. The corner of the package registering with the cut-away corner of the body, is 70 designed to be torn away at T in the usual manner to expose the cigarettes C. In order to close and cover the torn-away corner T, a cover element 22 is hinged at 23 to the cross rail 14. A spring lock is employed for holding the cover in either its open or closed position, and consists of a leaf spring 24 carried by the hinged portion of the cover for engagement with the upper and lower faces 25 and 26 of a lug 27 formed on and projecting 75 forwardly from the cross rail 14. The cover 22 is preferably constructed of sheet metal and, if desired, may be reinforced by an internal frame.

Within the upper portion of the front frame there is preferably mounted a sheet metal plate 28, the upper end of which projects slightly above the upper rail of the front frame so as to engage within the cover when closed.

90 From the foregoing it will be seen that a neat, attractive and effective holder for cigarette packages has been devised, which prevents the crushing of the package and its contents when carried in the pocket.

95 What is claimed is:

A cigarette package holder comprising a cage-like body including spaced parallel side and end bars, one pair of each of which are of lesser length than the remaining pair, 100 a pair of spaced bars connecting the ends of

said shorter pair of bars to define a cut away corner, transverse bars connecting said side and end bars and angularly disposed corner bars at the remaining corners, one of the transverse bars at one end of the holder being movable to a position to permit of the insertion of a cigarette package and nor-

mally movable to a position to retain the same within the holder, and a cover element for the cutaway corner adapted to close a torn-away corner of the package coinciding with the cutaway corner of the holder. 10

JOHN WOLFE.
